Philip S. McLean, ATTORNEY

UNITED STATES PATENT OFFICE.

FRANK RUTLEDGE DAVIS, OF SCARSDALE, NEW YORK.

TOURNIQUET.

Application filed October 4, 1922. Serial No. 592,237.

To all whom it may concern:

Be it known that I, FRANK RUTLEDGE DAVIS, a citizen of the United States, and a resident of Scarsdale, county of West Chester, and State of New York, have invented certain new and useful Improvements in Tourniquets, of which the following is a specification.

The objects of this invention are to provide a tourniquet of light, simple, sturdy construction which can be readily applied and removed, which will be capable of easy adjustments to fit various requirements and which will require no special skill in its handling.

In the accomplishment of the foregoing and other objects I have evolved a novel construction, combination and relation of parts, a practical example of which is disclosed in the accompanying drawing, where in Figure 1 is a plan view showing the ends of one of the tourniquets as approached, preparatory to connecting them together.

Figure 2 is a longitudinal sectional view showing the parts as engaged in the first or coupled position, and

Figure 3 is a side elevation showing the parts interlocked in the final secured relation.

In the illustration, the strap or band 5 which forms the body of the tourniquet is fixedly connected at one end with the end bar 6 of a frame, and has a sliding connection with a lever which is adapted for pivotal engagement with the frame.

For the purpose of a sliding, adjustable connection with the tightening lever, the strap is passed over a flat bar 7 extending at an intermediate point between the sides 8 of the lever frame, in the form of a loop about a rounded cross bar 9 at the end of the lever frame and beneath a flat cross bar 10 at the opposite end of the frame. This last-mentioned bar is located at the free swinging end of the lever and serves as a convenient handle for operating the lever. As shown in Figure 2 the two flat intermediate and end bars 7 and 10 are spaced apart a distance somewhat less than the double thickness of the strap so as to deflect the two sides of the loop out of the straight path and cause the strap to bind more or less.

At the end of the lever, where the strap is looped about the rounded cross bar 9

there are provided pivot studs 11 projecting outwardly beyond the sides of the frame which studs may in fact constitute outward extensions of the cross bar 9.

The frame which constitutes the pivotal mounting for the tightening lever is shown as constructed with upstanding sides 12 spaced to receive the lever between them and braced rigidly apart by the end bar 6 and two intermediate braces 13, 14. The lower or inner edges of these sides and the braces 13, 14 may be arranged on an easy curve, as indicated in Figures 2 and 3.

The pivot studs 11 at the end of the tightening lever seat in open bearings 15 provided in the upper edges of the frame sides 12, and the lever is held in the strap tightened position by the engagement of outstanding lugs 16 at the free end of the lever engaging beneath overstanding shoulders 17 forming part of the open bearings 18 in the sides of the frame positioned to receive such locking studs.

The two parts described thus constitute in their general effect the elements of a buckle having a tongue which can be turned over to tighten the strap.

The strap end which is engaged with the lever may be passed beneath a bar 19 at the end of the frame opposite that to which the strap is permanently attached and this bar is shown as having a gap 20 therein to enable the engagement of the strap beneath the same while the lever remains attached to the strap.

By making the lever and its base as two completely separate but readily engageable parts, each connected with an end of the strap, it is possible to apply the tourniquet very easily, by simply passing the two ends about the injured member, slipping the lever end of the strap edgewise through the gap in the end of the base and then hooking the pivot studs of the lever in the open bearings provided therefor in the base. As shown in Figure 2 the parts are then coupled together, but in such a way that the main slack can be taken up by simply pulling on the free end of the strap at 5^a, this because of the fact that in such position the strap extends as a simple loop about the rounded bar 9, and is free to pass between the intermediate and end bars 7 and 10. After this preliminary slack has been taken up the lever is turned over, as indicated in dotted

lines in Figure 2, into the fully reversed relation shown in Figure 3, where the stop lugs pass into sockets provided therefor in the base and beneath the overstanding shoulders.

As shown in Figure 3 the spacing between the bearing sockets and the locking sockets is preferably somewhat greater than the spacing between the pivot studs and the 10 locking studs so that in the final position the pull will come on the locking studs and so make the lock the more secure.

In turning over the lever in the strap tightening operation, the end of the strap 15 at 5^a may be used as a convenient hand-hold, it bending about the edge of the cross bar 10, as shown in the dotted lines in Figure 2. This prevents slippage of the strap while the lever is turning over and 20 until the strap becomes firmly held by the reverse bend over the intermediate bar 7, which is effected in the turning over of the lever. This abrupt bending of the strap over the bar 7, indicated at 5^b in Figure 3, 25 coupled with the fact that the tensioned strap overlies the loop about the bar 9, at 5^c, effectually prevents any slippage of the strap through the lever when the lever has 30 been turned to its locked position. If it is desired to release the tourniquet at any time this is easily done either by grasping the protruding end of the strap or the end of 35 the lever at 10 and swinging back the lever in the reverse direction, that is, toward the right in Figure 3.

The connecting means of this invention will be seen to consist of but two parts which though relatively light and simple can be made rigid and strong enough to 40 carry their respective loads and which can each be readily made in a single piece, as by molding, casting, pressing or the like.

What I claim is:

1. In a tourniquet, a strap holding base 45 and a strap tightening lever detachably engageable therewith, said lever having spaced bars with a strap having cooperating re-versely extending loops doubled over the same, whereby said strap can be friction- 50 ally secured in different adjustments, said lever further having pivotal engagement near one of its ends with the base and having means adjacent its opposite or free end 55 for interlocking engagement with cooperat-ing holding means on the base.

2. In a tourniquet, a strap holding base having upstanding sides spaced to receive a tightening lever therebetween and provided with open bearing sockets and locking 60 sockets spaced apart in the upper edges thereof, a strap tightening lever detachably engageable with the base between the up-standing sides and having bearing lugs at one end for engagement in the bearing 65 sockets and locking shoulders spaced therefrom

to snap into the locking sockets, said lever having transversely arranged spaced rigid bars adapted to frictionally retain a strap looped thereover.

3. The device of claim 1 with the strap 70 connected with one end of the base, the base having a transverse bar adjacent its opposite end, having a gap for the ready passage of the strap.

4. In a tourniquet, a frame having a cross bar at one end for the attachment of a strap and a cross bar at the opposite end having a gap therein, said frame having upstanding sides with bearing sockets and locking sockets spaced longitudinally from said bearing 80 sockets and a lever frame having spaced sides connected at one end by a strap holding bar and at the opposite end by a finger-hold, said lever further having an intermediate strap engaging bar between the end 85 bar and finger-hold with pivot pins substantially in line with the end bar for engagement in the bearing sockets and locking shoulders for engagement in the locking 90 sockets.

5. The structure of claim 1 in which one of the strap holding bars of the lever is located adjacent one end of the lever and has a rounded edge for a loop of the strap to slide thereover and in which another strap holding bar is substantially flat and is located near the opposite end of the lever. 95

6. The structure of claim 1 in which the base has a strap engaging bar provided with a gap for the ready passage of the strap. 100

7. The device of claim 2 with the bearing sockets and locking sockets spaced more widely apart than the bearing lugs and locking lugs on the lever.

8. The device of claim 2 with the bearing sockets and locking sockets spaced more widely apart than the bearing lugs and locking lugs on the lever and in which the locking sockets have shoulders overstanding the locking shoulders of the lever. 110

9. The device of claim 2 with a strap engaging bar on the base provided with a gap for the passage of the strap.

10. In a tourniquet, a strap-holding base having upstanding sides spaced apart and provided in the edges thereof with open bearing sockets and open locking sockets spaced therefrom, shoulders partly over-standing said locking sockets and a strap-tightening lever having means for adjust- 115 ably securing the strap thereto with bearing lugs detachably engageable in the open bearing sockets and locking shoulders positioned to ride over the shoulders of the locking sockets and into seated engagement in the 120 locking sockets as the strap-tightening lever is swung over to tighten the strap.

11. In a tourniquet, a strap-holding base and a strap-tightening lever pivotally engaged therewith, said lever having a trans- 130

verse bar near its pivotal axis and a second transverse bar spaced therefrom and removed from the pivotal axis, with a strap passed over the second bar and looped about 5 the first bar, whereby in one position of the lever the strap will slide freely over said bars for purposes of adjustment and whereby

when the lever is swung in a direction to loop the strap about the second bar, the strap will be frictionally held.

In witness whereof, I have hereunto set my hand this 26th day of September, 1922.

F. RUTLEDGE DAVIS.
